UNITED STATES PATENT OFFICE.

BENJAMIN H. GROSSMAN, OF PROVIDENCE, RHODE ISLAND.

DESIGN FOR A BUTTON.

61,093.

Specification for Design. Patented June 20, 1922.

Application filed April 4, 1922. Serial No. 1,527. Term of patent 3½ years.

To all whom it may concern:

Be it known that I, BENJAMIN H. GROSSMAN, a citizen of the United States, residing at Providence, in the county of Providence and State of Rhode Island, have invented a new, original, and ornamental Design for a Button, of which the following is a specification, reference being had to the accompanying drawings, forming a part thereof.

The figure is a front elevation of a button showing my new design.

I claim:

The ornamental design for a button as shown.

In testimony whereof I affix my signature.

BENJAMIN H. GROSSMAN.
